UNITED STATES PATENT OFFICE.

JOHN HOLLAND LETZ, OF CROWN POINT, INDIANA, ASSIGNOR TO THE LETZ MANUFACTURING COMPANY, OF CROWN POINT, INDIANA, A CORPORATION OF INDIANA.

GRINDING-BUR.

1,244,513.

Specification of Letters Patent. Patented Oct. 30, 1917.

Application filed January 17, 1917. Serial No. 142,800.

To all whom it may concern:

Be it known that I, JOHN HOLLAND LETZ, a citizen of the United States, and a resident of Crown Point, in the county of Lake 5 and State of Indiana, have invented certain new and useful Improvements in Grinding-Burs, of which the following is a full, clear, and exact specification.

My invention is concerned with grinding 10 burs of the type shown in the Letz Patent No. 437,699, and is designed to produce a bur that will grind more rapidly and economically than can be done with the bur having the dress shown in the aforesaid 15 patent.

To illustrate my invention, I annex hereto a sheet of drawings, in which the same reference characters are employed in all the figures, and in which,—

20 Figure 1 is a view of the complete face of the bur;

Fig. 2 is a section on the line 2—2 of Fig. 1; and

25 Fig. 3 is an enlarged view of the portion of the face shown in Fig. 1.

The body of the bur preferably consists of a thin annular casting, which may be reinforced on its back with one or more annular ribs *r*. Its grinding surface is generally 30 flat, except as it is broken by the grinding ribs hereinafter described, which it will be understood are ordinarily cast integral with the body and ground off so as to form cutting edges and grinding surfaces on all of 35 them in the same plane, which edges and surfaces are adapted to coöperate with similar edges and surfaces similarly formed on the similar ribs on the opposed face of the companion bur.

40 The ribs are preferably arranged in groups, substantially triangular in their general outline, and preferably six in number. The ribs going to make up each of the six groups preferably have the same design, or substantially so, so that description of one group will suffice for all.

Considering a central vertical line through Figs. 1 and 3 as the base line for the purposes of description, the main ribs *a*, *b*, *c*, *d* 45 and *e* are parallel to each other and extend at an angle of about sixty degrees to said base line. They are preferably interrupted, and thus made up of a plurality of sections, such as *a*, *a'*, *a²*, *a³*, *b*, *b'*, *b²*, *b³*, *c*, *c'*, *c²*, *d*,

d', *d²*, *e*, *e'* and *e²*; while the baffle ribs *f*, *g*, *h*, *j* and *k* are preferably arranged in parallel series: *f*, *f'*, *f²*, *f³*, *g*, *g'*, *g²*, *g³*, *h*, *h'*, *h²*, *h³*, *h⁴*, *j*, *j'*, *j²*, *j³*, *j⁴*, *k*, *k'*, *k²* and *k³*, and are angular in their general design, the angles being preferably right angles, and the angles of the alternate series pointing in opposite directions. The various series of ribs of each of the sixty-degree sections begin at such a distance from the center of the disk as to leave the triangular plain spaces between each adjacent pair of sections, thus facilitating the start of the centrifugal movement of the grain outward to the peripheries of the burs.

In operation, the grinding is mainly effected by the angular ribs *f*, *h*, *k*, *f'*, *h'*, *k'*, etc., while the angular ribs *g*, *j*, *g'*, *j'*, etc., facing the other way are mainly baffle ribs in their action, although they do some grinding. Similarly, the ribs *a*, *b*, *c*, *d*, *e*, *a'*, *b'*, *c'*, *d'*, *e'*, etc., serve mainly to force the grain being ground outward, although they too have some shearing action. The combined action of these three sets of ribs in the two burs produces a very efficient grinding apparatus for even so difficult a substance as cotton seed.

What I claim as new, and desire to secure by Letters Patent of the United States, is:

1. A grinding bur consisting of a generally flat disk having a series of grinding ribs projecting therefrom and having their flat top surfaces in the same plane and forming shearing edges, said ribs being arranged in plural series of parallel ribs separated by angular ribs having their angles alternately facing in opposite directions.

2. A grinding bur consisting of a generally flat disk having a series of grinding ribs projecting therefrom and having their flat top surfaces in the same plane and forming shearing edges, said ribs being arranged in plural series of parallel ribs interrupted at intervals and separated by angularly disposed ribs having their angles alternately facing in opposite directions.

In witness whereof, I have hereunto set my hand and affixed my seal, this 16th day of December, A. D. 1916.

JOHN HOLLAND LETZ. [L. S.]
